FIREARM HAVING A FOLDING BUTT STOCK

George C. Sullivan, 3085 Lake Hollywood Drive,
Hollywood, Calif.

Filed Sept. 10, 1963, Ser. No. 76,546

Term of patent 14 years

(Cl. D30—1)

FIG. 1 is a side elevational view of a firearm having a folding butt stock, showing my new design.

FIG. 2 is a top plan view thereof showing the butt stock in folded position.

FIG. 3 is a side elevational view opposite to that of FIG. 1 showing the stock in the folded position.

The rear end of the butt stock is substantially plain in appearance.

The essential feature of the disclosed design resides in the butt stock portion shown in full lines as illustrated.

This application is a continuation-in-part of my pending application Ser. No. D. 65,596, filed June 14, 1961, now abandoned in favor of this application.

I claim:

The ornamental design for a firearm having a folding butt stock, substantially as shown and described.
